[57] CLAIM

The ornamental design for a bed, substantially as shown and described.

DESCRIPTION

FIG. 1 is a perspective view of a bed showing my new design;

FIG. 2 is a top plan view thereof with a portion of the top broken away;

FIG. 3 is a rear elevational view thereof;

FIG. 4 is a side elevational view, the opposite side being a mirror image thereof;

FIG. 5 is a front elevational view thereof;

FIG. 6 is a cross-sectional view taken along line 6—6 of FIG. 4;

FIG. 7 is a perspective view of a bed showing a modified form of my new design; and

FIG. 8 is a top plan view of the embodiment of FIG. 7 with a portion of top broken away.

FIG. 2

FIG. 4

FIG. 3

FIG. 6

FIG. 5

FIG. 7
